UNITED STATES PATENT OFFICE.

BRUNO EDWARD MARSHALL, OF WILLIAMS, ARIZONA, ASSIGNOR OF ONE-FOURTH TO
FRANK A. BALDWIN AND ONE-FOURTH TO VICTOR M. TUTHILL, BOTH OF GRAND
RAPIDS, MICHIGAN, DOING BUSINESS UNDER THE FIRM-NAME BALDWIN, TUT-
HILL AND BOLTON.

LIMITING AND STOPPING DEVICE.

1,106,574.

Specification of Letters Patent. Patented Aug. 11, 1914.

Application filed September 22, 1913. Serial No. 791,211.

To all whom it may concern:

Be it known that I, BRUNO EDWARD MARSHALL, a subject of the Emperor of Germany, residing at Williams, in the county of Coconino and State of Arizona, United States of America, have invented certain new and useful Improvements in Limiting and Stopping Devices; and I do hereby declare the following to be a full, clear, and exact description of the invention, such as will enable others skilled in the art to which it appertains to make and use the same.

My invention relates to improvements in limiting and stopping devices for the feed mechanism of automatic machinery and particularly to such machinery as automatic knife grinders and the like, and its object is to provide a device of this character which will stop the feeding mechanism of the machine after it has traveled a predetermined distance, to provide a device which will be simple in construction and operation, and to provide the same with other new and useful features hereinafter more fully described and particularly pointed out in the claims.

In certain classes of wood working machinery, such as planers, etc., in which more than one knife is attached to a rapidly rotating head, it is necessary that these knives be exactly the same weight so that the head with the knives attached thereto will be perfectly balanced and will run smoothly when rotating at a high speed. It is, therefore, necessary when the knives are sharpened, to grind exactly the same amount of material from each knife so that they will remain exactly the same weight. The usual method of maintaining the knives the same weight has been to carefully weigh them after they have been sharpened, and should one knife be heavier than the other, it is again placed in the grinding machine and sufficient material ground away to make it exactly balance the lighter knife. This method was objectionable because it was often necessary to replace the knife in the grinding machine several times before an exact balance of the knives was obtained. My invention overcomes this objectionable method by providing automatic stopping means on the feeding mechanism of the grinding machine, by which the said feeding mechanism is thrown out of operation

after it has traveled forward a certain predetermined distance and consequently by adjusting this stopping device the same for each knife the same amount of material will be ground away from each of the knives, and they will retain their uniform weight.

The preferred construction and arrangement of this stopping device is clearly shown in the accompanying drawings in which:— Figure 1 is a plan view of an automatic knife grinding machine with my improved stopping device applied thereto; Fig. 2 is a front elevation of the same; Fig. 3 is an enlarged transverse section of a portion of the grinding machine showing the stopping device in operative position; Fig. 4 is an enlarged plan, partially in section of a portion of the machine and the stopping device; and Fig. 5 is an enlarged transverse section of the stopping device showing the feeding pawl lifted out of engagement with the ratchet wheel.

Like numbers refer to like parts in all of the figures.

1 represents the frame of a grinding machine which has a grinding wheel 2 and a reciprocating carriage 3. A tilting table 4 is located before the grinding wheel and is supported at its respective ends by trunnions journaled in supports 5, which are movable transversely of the carriage on ways 6. These supports 5 are automatically moved toward or from the grinding wheel by means of feed screws 7 and these feed screws are in turn rotated from a shaft 8 through the worm gears 9 and 10. The shaft 8 is rotated step by step at the end of each alternate reciprocation of the carriage 3 by means of a ratchet wheel 11 attached to the shaft and engaged by a pawl 12 on one end of a lever 13. The opposite end of this lever engages a stationary cam 14 at the end of each alternate stroke of the carriage and is moved thereby which causes a partial rotation of the shaft 8, and when the lever 13 is released as the carriage moves on its return stroke, it is returned to normal position by means of a spring 15.

The stopping device is for the purpose of raising the pawl 12 from engagement with the ratchet wheel 11, after the table 4 has been moved a predetermined distance toward the grinding wheel and it comprises a star wheel 16 journaled in a housing 17

2

and provided with a spring actuated detent 18, which prevents inadvertent rotation of the wheel. A pin 19 projecting from the face of the ratchet wheel 11 is so arranged that it will engage one tooth of the star wheel at each rotation of the ratchet wheel and rotate the star wheel the space of one tooth. A lifting lever 20 is pivotally attached at one end to the side of the housing 17 and its free end is adapted to engage a pin 21 which projects from the pawl 12. A cam 22 is provided on the shaft 23 of the star wheel and rotates with said wheel. This cam engages a projection 20^a on the lifting lever, and at a certain position of the star wheel the cam raises the lever 20 and lifts the pawl 12 out of engagement with the ratchet wheel 11. A blank space 16^a having no teeth is provided on the periphery of the star wheel and so located that after the lever 20 has been raised by the cam 22, the pin 19 will move freely opposite the said blank space at each rotation of the ratchet wheel and will have no effect upon the star wheel. This permits manual adjustment of the machine by rotating the shaft 8 by the hand wheel 8^a without affecting the position of the star wheel 16. To facilitate adjusting the stopping device, numerals are stamped on the face of the star wheel opposite each of the teeth thereon, and these numerals appear through an aperture 24 in the housing 17. A knob 25 is also provided on the shaft 23 so that the star wheel may be adjusted to the desired position when setting the device.

The operation of the device is as follows:—The operator attaches one knife of a set to the table 4, and then rotates the shaft 8 manually by means of the hand wheel 8^a which moves the table forward until the knife 25 engages the grinding wheel 2. The machine is then set in motion and the knife is ground sufficiently to sharpen it. During this operation the shaft 8 is rotated step by step as heretofore described and at each rotation of the ratchet wheel 11 the star wheel 16 is rotated one tooth. When the operator considers the first knife sufficiently ground the machine is manually stopped and the position of the star wheel is noted. The next knife of the set is then attached to the table and likewise brought in contact with the grinding wheel, and the star wheel is then manually rotated until the numeral thereon representing the number of teeth which were moved during the former operation appears through the opening 24 and the machine is again put in operation. The above described operation is repeated until the star wheel has been rotated the number of teeth indicated by the numeral at which it was set, at which point the cam 22 will engage 65 the projection 20^a on the lever 20 and raise

the same, lifting the pawl 12 out of engagement with the ratchet wheel whereupon the operation of the feeding mechanism is arrested and the grinding of the knife ceases. Each subsequent knife in the set is submitted to the same process and consequently they are uniformly ground and remain the same weight and balance.

What I claim is:—

1. In combination with feeding mechanism having both automatic means and manual means for separately operating the same, means for automatically and wholly disengaging the automatic means from the feed mechanism at a predetermined point in its operation, whereby the feed mechanism may be manually operated without operating the automatic means.

2. In combination with feed mechanism having both pawl and ratchet means and manual means for separately operating the same, means for automatically disconnecting the pawl from the ratchet at a predetermined point in its operation and automatic means for disconnecting the feed mechanism and said automatic means to permit independent manual operation of the feed mechanism without affecting the automatic means.

3. In combination with feeding mechanism having both pawl and ratchet mechanism and manual means for separately operating the same, a lever to disconnect the pawl from the ratchet, a star wheel rotated by the ratchet wheel, and operating the lever, and means for simultaneously disconnecting the star wheel and the ratchet when the lever disconnects the pawl, whereby the feed mechanism may be manually operated without affecting the automatic mechanism.

4. In combination with a feeding mechanism driven by a pawl and ratchet of a wheel rotated by the said ratchet, a cam rotated by the wheel and a lever moved by the cam to disengage the pawl from the ratchet.

5. In combination with feeding mechanism driven by a pawl and ratchet wheel of a stopping device, comprising a star wheel, a pin on the ratchet wheel to engage the star wheel to actuate the same, a cam in fixed relation to the star wheel, a pivoted lever actuated by the cam and a pin projecting from the pawl and engaged by the lever whereby the pawl is disengaged from the ratchet at a predetermined point.

6. In combination with a feeding mechanism driven by a pawl and ratchet wheel, of a stopping device comprising a pin projecting from the pawl, a pivoted lever to engage the pin, a cam to actuate the lever, a star wheel to rotate the cam, said star wheel having a blank space on its periphery arranged to be opposite the ratchet wheel when the lever is raised by the cam, and a

pin projecting from the ratchet wheel to engage the star wheel to actuate the same.

7. In combination with a feeding mechanism driven by a pawl and ratchet wheel of
5 a stopping device comprising a star wheel rotatable within a housing, and having a blank space on its periphery, a pin projecting from the ratchet wheel to engage the star wheel to actuate the same, a cam in
10 fixed relation to the star wheel, a pivoted lever raised by the cam when the blank space on the star wheel is moved opposite the ratchet wheel, a pin projecting from the

pawl engaged by the lever, a yieldable detent to prevent inadvertent rotation of the 15 star wheel, an aperture in the housing, and numerals opposite the respective teeth of the star wheel appearing successively through the said aperture as the star wheel is rotated.

20 In testimony whereof I affix my signature in presence of two witnesses.

BRUNO EDWARD MARSHALL.
